Patented Oct. 17, 1922.

Inventor
WILLIAM H. NOTTAGE
By his Attorney *John J. Adams*

UNITED STATES PATENT OFFICE.

WILLIAM HOCKLEY NOTTAGE, OF CHELMSFORD, ENGLAND, ASSIGNOR TO RADIO CORPORATION OF AMERICA, A CORPORATION OF DELAWARE.

RADIOSIGNALING APPARATUS.

Application filed March 30, 1921. Serial No. 456,882.

To all whom it may concern:

Be it known that I, WILLIAM HOCKLEY NOTTAGE, a British subject, and a resident of Chelmsford, England, have invented certain new and useful Improvements in Radiosignaling Apparatus, of which the following is a specification accompanied by drawings.

This invention relates to a system of telephony including both land lines and wireless, and its object is to provide an improved system whereby signals received by wireless may be transmitted over land lines and whereby a wireless transmitter may be operated by signals transmitted over land lines.

According to my invention I provide a Wheatstone bridge each of two adjacent arms of which is formed of one winding of a transformer, such, for instance, as those used in land line telephony for connecting the receiver to the line. To two opposite junctions of the bridge I connect the wireless receiver and to the other two junctions I connect the wireless transmitter, and I connect the land line to the other winding of the transformer of one arm.

With this arrangement signals coming in to the wireless receiver will not affect the wireless transmitter but will affect the land line so that they can be heard over that land line. Signals transmitted over the land line will not affect the wireless receiver but will affect the wireless transmitter by which they will be transmitted, because the latter is responsive to audible frequencies and the former is only affected by radio frequencies from the antenna.

The second inductive arm of the bridge is preferably formed of one winding of a transformer exactly similar to that connecting the land line already mentioned to the bridge.

It may be necessary to balance the land line by an artificial line in this second transformer, and by providing a microphone and telephone in this line an engineer or operator at the wireless station is enabled to supervise the working. Thus he can listen in to signals received from the wireless receiver or land line and can also operate the wireless transmitter through the bridge.

In the accompanying diagram A, B, C, D is a bridge, two arms, A and B, including

the secondary windings A' and B' of two similar transformers, the windings preferably being of high inductance.

R and R' are resistances included in arms A and B for purposes of balancing. In the other arms C and D are two impedances, such as condensers C' and D', one or both being variable; they may conveniently be air condensers of the kind used in wireless telegraph receivers.

To the primary winding A'' of the transformer in arm A, which primary winding should be of the same order of inductance and resistance as the transformers usually associated with land telephone lines, is connected a land telephone line E to a telephone exchange or subscriber.

To the primary winding B'' of the transformer in arm B is connected an artificial telephone line F which may be adjustable and of magnitude suitable to balance the effect of the land line E. To this artificial line may be connected an ordinary land telephone subscriber's set G or a microphone and telephone of any suitable pattern.

The junction H of arms A and B and the junction J of arms C and D are connected by leads, which may be screened in metal casing, to the receiver of a wireless telephone set with the addition of any magnifiers required to bring the strength of received signals to a value sufficient to be heard at the subscriber's instrument in the line E.

The junctions K of arms A and C, and L of arms B and D, are joined by leads, which may be screened by metal casing, to that circuit of the wireless telephone transmitter usually associated with the microphone, with the addition of any magnifiers required to bring the intensity of speech received from the land line to a value suitable for actuating the wireless telephone transmitter.

Resistances M N and condenser Q may be provided to join one diagonal, say K L, of the bridge, and a point between M and N may be brought to earth potential or some suitable potential with reference to the wireless telephone set.

The bridge is balanced by adjusting the arms A, B, C and D so that signals from the wireless telephone receiver do not affect the wireless transmitter. This adjustment

may be found by connecting a telephone to the leads K and L and adjusting the arms until no signals are heard.

When speech is impressed on the transmitter from the land line, the receiver will not be affected even if speech frequencies do get into it as it is only affected by radio frequencies from the antenna circuit.

Having described my invention what I claim is:-

1. In radio signaling apparatus, a Wheatstone bridge having transformer windings in two adjacent arms, a telephone line connected to the other winding of one of the 15 transformers, a wireless telephone receiver connected to two opposite junctions between the arms of the bridge and a wireless telephone transmitter connected to the other two opposite junctions.
2. In radio signaling apparatus, a Wheatstone bridge having transformer windings in two adjacent arms, a telephone line connected to the other winding of one of the 20 transformers, a wireless telephone receiver having one terminal connected to the junction of the adjacent arms containing the transformer windings and the other terminal connected to the opposite junction of the bridge, and a wireless transmitter connected to the other two opposite junctions of the bridge.
3. In radio signaling apparatus a Wheatstone bridge having transformer windings in two adjacent arms, a telephone line connected to the other winding of one of the 25 transformers, a balancing line connected to the other winding of the other transformer, a wireless telephone receiver connected to two opposite junctions between the arms of the bridge and a wireless telephone transmitter connected to the other two opposite junctions.
4. In radio signaling apparatus, a Wheatstone bridge having transformer windings in two adjacent arms, a telephone line connected to the other winding of one of the 30 transformers, a balancing line connected to the other winding of the other transformer, a wireless telephone receiver having one terminal connected to the junction of the adjacent arms containing the transformer

windings and the other terminal connected to the opposite junction of the bridge, and a wireless transmitter connected to the other opposite junctions of the bridge.

5. In radio signaling apparatus a Wheatstone bridge having transformer windings in two adjacent arms, impedances in the other two adjacent arms, a telephone line connected to the other winding of one of the 55 transformers, a wireless telephone receiver connected to two opposite junctions between the arms of the bridge, and a wireless telephone transmitter connected to the other two opposite junctions.

6. In radio signaling apparatus, a Wheatstone bridge having transformer windings in two adjacent arms, and condensers in the other two adjacent arms, a telephone line connected to the other winding of one of the 60 transformers, a wireless telephone receiver connected to two opposite junctions between the arms of the bridge and a wireless telephone transmitter connected to the other two opposite junctions.

7. In radio signaling apparatus, a Wheatstone bridge having transformer windings in two adjacent arms, a telephone line connected to the other winding of one of the 65 transformers, a wireless telephone receiver connected to two opposite junctions between the arms of the bridge, a wireless telephone transmitter connected to the other two opposite junctions, and impedances connected across two opposite junctions of the bridge, and means for grounding an intermediate 70 point of such impedances.

8. In radio signaling apparatus, a Wheatstone bridge having transformer windings in two adjacent arms, a telephone line connected to the other winding of the 75 transformers, a balancing line connected to the other winding of the other transformer, a wireless telephone receiver connected to two opposite junctions between the arms of the bridge, a wireless telephone transmitter connected to the other two opposite junctions and means in said balancing line for controlling said receiver and transmitter.

WILLIAM HOCKLEY NOTTAGE.
